UNITED STATES PATENT OFFICE.

DANIEL O. FOSGATE, OF ROCHESTER, MINNESOTA.

TUG-BUCKLE.

SPECIFICATION forming part of Letters Patent No. 228,255, dated June 1, 1880.

Application filed February 26, 1880.

To all whom it may concern:

Be it known that I, DANIEL O. FOSGATE, of Rochester, in the county of Olmsted and State of Minnesota, have invented a new and 5 useful Improvement in Tug-Buckles, of which the following is a specification.

Figure 1 is a plan view of the improvement. Fig. 2 is a longitudinal section taken through the line *x x*, Fig. 1. Fig. 3 is a cross-section 10 taken through the line *y y*, Fig. 1.

Similar letters of reference indicate corresponding parts.

The object of this invention is to furnish 15 tug-buckles so constructed as to distribute the strain and prevent the tongue-holes from tearing or cutting out, and which will allow the trace to be readily lengthened and shortened, and will not be liable to become accidentally unfastened.

20 The invention consists in constructing the buckle-frame with loops to receive the harness-straps, with its front cross-bar notched, its rear cross-bar beveled, and with flanges or plates upon the inner sides of its side bars to receive the tug, and in constructing the tongue-piece with its forward end curved, its rear edge wedge-shaped, and with a tongue, so that the tug will be securely clamped and held 25 between the said flanges or plates and the 30 said tongue-piece, as will be hereinafter fully described.

A represents the trace, B the hame-tug, and C the loop or keeper through which the free end of the tug A is passed.

35 D is the frame of the buckle, upon the upper bar of which is formed a loop, E, to receive the back-strap. Upon the lower bar of the frame D is formed a loop, F, to receive the belly-band strap. Upon the rear bar of the 40 frame D is formed a loop, G, to receive the breeching-strap, and upon its front bar is formed a loop, H, to receive the hame-tug B. The front and rear bars of the frame D project outwardly, to allow the tug A to be passed between them and the plates or flanges I, formed 45 upon the inner sides of the side bars of the frame D, and the inner edges of which are at such a distance apart as to receive between them the tongue J, formed upon the tongue-

piece K. The forward end of the tongue-piece 50 K is made narrow, is slightly curved outward, and has a longitudinal rib formed upon its outer side to enter a transverse groove or notch in the inner side of the front bar of the frame D to prevent the tongue-piece K from 55 having any lateral movement. The middle part of the tongue-piece K has a shoulder, k, formed upon it to strike against the front cross-bar of the frame D and limit the forward movement of the said tongue-piece K. The rear 60 end of the tongue-piece K is inclined upon its outer side or made wedge-shaped, and the inner side of the rear cross-bar of the frame D is correspondingly beveled, as shown in Fig. 2, so that when the tongue-piece is drawn back 65 by a draft strain upon the trace A the said trace will be clamped between the flat inner side of the tongue-piece K and the plates or flanges I and the tongue J, and the tongue-holes of the trace A will be relieved from the 70 strain. Upon the outer side of the rear part of the tongue-piece K is formed a loop, L, to serve as a handle in operating the said tongue-piece. In securing the trace the said trace is passed beneath the rear and front cross-bars 75 of the frame D and through the keeper C. The forward end of the tongue-piece K is inserted beneath the front cross-bar of the frame D. The tongue J is inserted in a tongue-hole, and the trace and tongue-piece are pushed 80 forward until the rear end of the tongue-piece K can be inserted beneath the rear cross-bar of the frame D. The trace and tongue-piece are then drawn back until the trace is firmly 85 clamped between the tongue-piece K and the flanges or plates I. By reversing this operation the tongue-piece K can be detached and the trace A removed or adjusted, as may be required.

I am aware that it is not new to construct 90 a buckle with a frame having side and end loops and provided with a wedge carrying a stud for the purpose of securing straps, and such I do not claim, broadly.

Having thus described my invention, I claim 95 as new and desire to secure by Letters Patent—

In a tug-buckle, the combination of the

frame D, constructed as described, having loops E F G H and flanges I, with the piece K, having tongue J, loop L, a long rib on the outer side fitting a groove in the cross-bar of the frame D, a shoulder, k, that strikes the front bar of said frame, and an incline on the outside to correspond with a bevel on the frame, all

constructed as shown and described, to adapt the buckle to work in connection with a trace and tug-strap, as specified.

DANIEL O. FOSGATE.
